SMOKING PIPE

Frank Hodgekins Silverthorne, New York, N. Y.

Application December 13, 1937, Serial No. 179,407

1 Claim. (Cl. 131—225)

This invention relates to smoking pipes and has for its object to provide an improved and simplified pipe which will be maintained "sweet" while in use; which can be easily cleaned; and which is provided with improved means for trapping juices, either from the tobacco bowl or from the mouth of the user, and for readily and quickly draining such juices from time to time as may be necessary.

10 Smoking pipes as now generally constructed become objectionable largely because the briar wood of which they are usually made readily absorbs the oily and tarry tobacco condensates and give rise to what is commonly referred to as a wet, soggy heel or moisture in the bowl, which is characteristic of a strong pipe. Many suggestions have been made for providing such pipes with various forms of metal liners which, of course, tend to prevent contamination of the wood; but, as heretofore constructed, these metal liners have been designed primarily to permit the smoke to pass therefrom but have not been provided with adequate means for isolating or discharging accumulated juices from the pipe, with the result that they have not eliminated the harsh, bitter taste of oils and tars or prevented tobacco dust and flakes from being drawn into the mouth. Another disadvantage of multi-chambered pipes as heretofore designed has been that they have been extremely complicated in construction and necessarily expensive to manufacture.

My invention avoids these disadvantages of the prior art by providing in the shank of the pipe, or partly in the shank and partly in the bit, a relatively long condensing chamber for removing and trapping nicotine oils and tars received from the bowl of the pipe, and from which chamber the smoke is drawn into a smoke cooling chamber in or adjacent the bit end of the stem and wherein the smoke is permitted to circulate before being withdrawn, and into which is discharged any saliva or moisture from the mouth of the smoker. When the pipe is smoked, of course, the bowl is usually tilted lower than the bit in the mouth, which allows the saliva to drain continuously from the cooling chamber into the condensing chamber, and this draining action is promoted by an improved funnel-shaped device associated with the cooling chamber as herein-after described. After each pipe-full of tobacco has been consumed, the accumulated oils and juices in the condensing chamber are easily discharged by simply disjointing the bit from the shank of the pipe and pouring the liquids out of

the condensing chamber. The simplified construction of this pipe, with a minimum number of removable parts, as hereinafter described, also facilitates cleaning of the pipe as occasion requires.

These and other features and advantages of the invention will be described in connection with the accompanying drawing, in which:

Fig. 1 is a view in vertical axial section through a tobacco pipe embodying the invention; 10

Fig. 2 is a similar view showing the stem detached from the shank of the pipe; and

Figs. 3 and 4 are similar sectional views illustrating two different modifications of the invention. 15

The pipe shown in Figs. 1 and 2 comprises a tobacco bowl 1 provided with the usual tobacco chamber 2 and with an integrally extending neck or shank 3 forming the inner end of the stem which terminates in a bit 4. 20

The shank 3 of the pipe is provided with a bore extending therethrough which comprises an enlarged outer cylindrical portion 5 of substantial diameter terminating at its inner end in a wall 6 through which extends a relatively constricted portion 7 of the bore opening into the bottom of the tobacco chamber 2. 25

A small diametered tube 8 extends through the wall 6 and projects into the constricted portion 7 of the bore which leads to the bottom of the tobacco chamber 2. This tube 8 also projects to the right in Fig. 1 a considerable distance beyond the wall 6 into the enlarged portion 5 of the bore which constitutes the oil trap or condensing chamber as hereinafter described. 30

At the outer end of the shank 3 there is provided a sleeve 9 of cylindrical shape, one end of which is threaded at 10 to engage corresponding threads in the wall of the condensing chamber 5 and lines or partly lines said chamber, while the outer ends project beyond the end of the shank 3 and is threaded at 12 for attachment to the bit as hereinafter described. The sleeve 9 is also provided with an intermediate flat-faced disc or flange 13 which abuts against the end of the shank 3 and serves as a seat for the adjacent end of the bit 4 when the parts are assembled as shown in Fig. 1 of the drawing. 40

The bit 4 is provided with a bore 14 of relatively small diameter, which communicates with a smoke cooling chamber 15 of considerably enlarged diameter adjacent the inner end of the bit. The inner end of the bit is counterbored at 16 to accommodate a lining 17 which is inserted under heat and pressure and is frictionally held 45

in this position as best illustrated in Fig. 2. The outer end of the liner 17 is internally threaded at 18 to engage the threads 12 of sleeve 9, and at its inner end it is internally threaded at 19 to receive a spout or funnel 20 which is considerably smaller in diameter than sleeve 9 and is adapted to project well within said sleeve when the bit 4 is screwed onto the shank of the pipe as illustrated in Fig. 1. The inner end of spout 20, comprising the inner terminus of smoke cooling chamber 15, is flared or funnel-shaped as illustrated at 21 for the purpose of facilitating the continuous drainage of saliva or moisture from the cooling chamber into the condensing chamber 5 as described below.

In the pipe described above and illustrated in Figs. 1 and 2, the tobacco smoke is condensed in the long chamber 5 in the shank of the pipe, thereby removing nicotine oils and tars, which are trapped therein. The smoke thus cleansed of impurities then passes through the spout 20 into the chamber 15 where the smoke is cooled before being drawn into the mouth. In order to accommodate the great majority of so-called "wet" smokers, who permit saliva to drain into the bit, the funnel 21 with its projecting spout 20 allows saliva to drain through the channel in the bit end of cooling chamber 15 and into the condensing chamber 5, where it is trapped with the oils and tars and held for removal. When the pipe is being smoked, the bowl 1 is almost always in a position lower than the bit in the mouth, thus allowing the saliva to drain through the funnel and into the condensing chamber. Also, the pipe is occasionally removed from the mouth and most smokers in doing so, tip the bowl downward, so that the pipe while being smoked if often tilted into a position which permits the saliva to drain into the condensing chamber 5 from which it is prevented from re-entering the bit and the mouth because of the appreciable space between the wall of condensing chamber 5 and the spout 20.

After each pipe-full of tobacco has been consumed, the liquids in condensing chamber 5 are easily discharged by simply disjointing the bit 4 while holding same pointed slightly upward, and pouring the liquids out of the condensing chamber. To facilitate pouring, the outer end of sleeve 9 is tapered to a sharp edge as illustrated at 22, which is adapted to abut against the wall of liner 17 when the bit and stem are assembled as shown in Fig. 1. This prevents any dripping and insures that the flange 13 where the bit and bowl stem join will always be kept clean. Accumulations of tar in condensing chamber 5 may be removed once or twice a week, or oftener as occasion requires, by inserting the blunt end of a pipe cleaner bent double and swabbing the side walls of the chamber around the tube 8. The smoke film in the cooling chamber 15 may be removed in a similar manner by simply unscrewing and removing the spout 20. Also, since the passages are all aligned, a pipe cleaner may be run directly through the pipe from the mouth end of the bit to the bowl, without disjointing the pipe, thus clearing the main channels of any tar or other obstructions.

In the embodiment of the invention shown in Fig. 3 the sleeve 9 is provided with an integral extension 24 which completely lines the wall of the condensing chamber and has an end wall 25 provided with a hole which registers with the bore 7 at the bowl end of the pipe and is just large enough to admit the tube 8, the shank of the pipe being otherwise similar to the construction shown in Figs. 1 and 2. In this form of the invention the condensing chamber, being completely metal lined, will prevent the oils and tars and other moisture from soaking into the brier of the shank 3. Also, since this metal chamber is somewhat cooler than the corresponding chamber in Figs. 1 and 2, it will cause a greater condensation of the smoke. The bit employed with this pipe may be and preferably is exactly like the bit shown to the right of Fig. 2; although, if desired, it may omit the cooling chamber and be provided simply with an internally threaded sleeve 26 cooperating with the sleeve 9 in the shank and with a spout 27 in alignment with the bore 14 of the bit and adapted to project into the condensing chamber in line with the tube 8.

In the embodiment of the invention shown in Fig. 4, the shank 3 of the pipe has a cylindrical condensing chamber 5 similar to that shown in Figs. 1 and 2 except that it is of larger diameter. The bit, however, is provided with a plug end 29 forming a tenon telescoping in the open end of the shank 3, instead of being screw-threaded as in the other forms of the invention. The smoke cooling chamber 15 is extended through the plug end of the bit, and a moisture draining spout or funnel 30 is fitted into this end of the cooling chamber and held therein by friction. In this form of the invention, as in those previously described, the oils, tars and other liquids trapped in the condensing chamber 5 are easily removed after each smoke by simply withdrawing the bit and tipping the shank of the pipe downward. It is unnecessary to shake the bit since the funnel 30 drains all the moisture from the cooling chamber 15 while smoking and prevents moisture from reentering the cooling chamber.

It is to be understood that various changes may be made in the details of construction herein shown and described without departing from the scope and spirit of the invention as defined in the appended claim.

The invention claimed is:

A separable pipe stem having a trap chamber therein, comprising a tube having a cylindrical inner wall terminating in a flanged portion having wall surfaces at substantially right angles to the cylindrical wall, and a tubular lining element for said chamber, one end of said lining element being removably engaged against said flanged portion, the outer wall of said lining element being tapered to said end whereby to provide a pouring edge, the tapered wall and the inner cylindrical wall providing a closed chamber, the walls of which are inaccessible to the liquids within the trap chamber.

FRANK HODGEKINS SILVERTHORNE.
